CLAIM

The ornamental design for a simulative bottle, as shown and described.

DESCRIPTION

FIG. 1 is a front elevational view of a simulative bottle showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front elevational view of a second embodiment of the bottle illustrated in FIG. 1 the only difference being the configuration of the cap;

FIG. 8 is a fragmentary left side elevational view shown for clarity of illustration thereof; and,

FIG. 9 is a top front perspective view of FIG. 1.
